UNITED STATES PATENT OFFICE.

SAMUEL P. WILLIAMS, OF HARTFORD, CONNECTICUT, ASSIGNOR TO THE HART & HEGEMAN MANUFACTURING COMPANY, OF HARTFORD, CONNECTICUT, A CORPORATION OF CONNECTICUT.

DESIGN FOR A CAP FOR AN ELECTRICAL DEVICE.

Application filed February 23, 1923. Serial No. 5,245. Term of patent 14 years.

To all whom it may concern:

Be it known that I, SAMUEL P. WILLIAMS, a citizen of the United States, residing in Hartford, Connecticut, have invented a Design for Cap for an Electrical Device, of which the following is a specification, reference being had to the accompanying drawings, forming part thereof, in which:

The figure is a perspective view of the cap for an electrical device forming the subject of my new, original, and ornamental design.

I claim:

The ornamental design for a cap for an electrical device, substantially as shown.

SAMUEL P. WILLIAMS.
